SHOE DISPLAY STAND OR SIMILAR ARTICLE

Louis Marcus, Newton, Mass., assignor to Marcus Window Display Service, Inc., Boston, Mass., a corporation

Application August 4, 1954, Serial No. 31,731

Term of patent 14 years

(Cl. D80—10)

FIG. 1.

FIG. 2.

FIG. 3.

I claim:

The ornamental design for a shoe display stand or similar article, substantially as shown.
